UNITED STATES PATENT OFFICE.

TELESPHORE JOSEPH SENESAC, OF CHICAGO, ILLINOIS.

ANCHOR FOR FLOOR SLEEPERS.

Application filed September 30, 1927. Serial No. 222,996.

The main objects of this invention are to provide an improved form of bar support; to provide an improved bar support and spacer particularly adapted for use in concrete construction work; to provide improved means for supporting floor sleepers; to provide improved means for anchoring the supporting means in the concrete; to provide improved spacing means; to provide improved fastening means for securing the sleepers to the supports; and to provide a device of this kind which combines the supporting, anchoring, spacing and fastening means in a durable unitary structure.

15 Illustrative embodiments of this invention are shown in the accompanying drawing, wherein:—

Figure 1 is a vertical fragmentary section of a concrete slab to which a sleeper is secured by an improved anchor, the dotted outlines representing the fastening means in their operative positions.

Fig. 2 is a perspective showing a sleeper secured to a slab by the improved anchor illustrated in Fig. 1.

Fig. 3 is a fragmentary perspective of one of the anchors shown in Figs. 1 and 2.

Fig. 4 is a view similar to Fig. 1, but showing a modified form of anchoring device.

30 Fig. 5 is a fragmentary perspective showing two floor sleepers supported on the modified form of anchor illustrated in Fig. 4.

Fig. 6 is a fragmentary perspective of the modified form of anchor shown in Figs. 4 and 5.

Fig. 7 is a perspective of another modified form of anchoring device to which this invention is applied.

In the forms shown, the improved anchors are used for supporting floor sleepers or bars 1 on a concrete slab 2. Floor sleepers are usually disposed in substantially parallel spaced relation to form a wooden frame structure to which the customary floor boards are 45 nailed.

In the forms shown, the improved anchoring devices comprise a supporting member which is provided with anchoring portions adapted to be embedded in the concrete or 50 other support, and seat portions which are adapted to support the sleepers and which are folded to provide fastening means for attachment to the sleepers.

The improved anchoring devices may be 55 made of any suitable material but are pref-

erably formed of wire rods which may be readily bent to the desired shape.

In the form shown in Figs. 1, 2, and 3, the anchoring device comprises a pair of supporting rods 3 arranged in substantially 60 parallel spaced relation. Each of the rods 3 is crimped at intervals to form a plurality of substantially V-shaped anchoring portions 4 which are arranged in pairs.

The portion of the rods 3 located between 65 the anchors 4 of each pair of anchors provides a seat 5 for engaging the sleepers 1, which are disposed longitudinally of the rods 3. Each of the seats 5 is folded upon itself to provide an arm 6, which may be bent at substantially 70 right angles to the seat 5 for engagement with the sleeper. Formed at the outer ends of the arms 6, are eyelets 7 for receiving nails 8 or other suitable fastening means which secure the sleepers 1 to the 75 anchoring devices.

The portions of the rods 3, located between the pairs of anchors 4, provide spacers 9.

Rigidly secured to the rods 3, is a plurality of substantially parallel spacing elements 10 80 arranged to hold the rods 3 in the desired spaced relation. The elements 10 may be spot-welded or otherwise secured to the rods 3 and are provided with depressions 11 for receiving the rods 3 so as to permit the rods 85 3 and cross spacers 10 to lie in substantially the same plane.

In the form shown in Figs. 4, 5 and 6, the anchoring device comprises a plurality of separately formed supporting devices 12 90 arranged in pairs and rigidly secured to a pair of substantially parallel spacing elements 13. Each of the supporting members 12 comprises a wire rod which is crimped to form a pair of substantially V-shaped 95 anchoring portions 14. The outer legs of the anchoring portions 14 are bent to form projections 15, which are welded or otherwise rigidly secured to the spacers 13. The inner legs of the portions 14 are bent to form 100 seats 16 for engaging the sleepers 1, and these seat portions 16 are folded upon themselves to form arms 17 adapted to be bent so as to embrace the sleepers. Formed at the outer ends of the arms 17, are eyelets 18 for receiving 105 nails 19 or other suitable fastening means, whereby the sleepers are secured to the anchoring devices.

With the improved construction shown in Figs. 4, 5, and 6, the rods 13 provide spacers 110

for spacing the supporting members 12 the desired distances apart.

In the form shown in Fig. 7, the anchoring device comprises a unitary structure made of a single piece of wire which is bent to form two pairs of anchors 20 arranged in substantially parallel spaced relation and connected together by integral spacing elements 21. The inner legs of the anchors 20 are bent 10 to form seats 22 and fastening arms 23 similar to those shown in Fig. 6.

In operation, after the concrete has been poured and before it has set, the improved anchoring devices are placed on the slab as 15 shown in full outline in Figs. 1 and 4. After the concrete has set, the sleepers are placed on the devices and the fastening arms are then bent upwardly to embrace the sleepers and to permit the nails to be driven into the 20 sides of the sleepers.

In certain anchoring devices heretofore in use, the fastening arms were welded to the supporting structure. Such devices were objectionable because, in bending the arms into 25 operative position, the welded joint was frequently broken. In the improved devices embodying this invention, the fastening arms are formed integral with the anchoring portions so that the foregoing objection to prior 30 devices is cured.

Although but certain specific embodiments of this invention have been herein shown and described, it will be understood that numerous details of the construction shown may be 35 altered or omitted without departing from the spirit of this invention as defined by the following claims.

I claim:

1. A device of the class described comprising a supporting member having a seat portion adapted to support a bar extending longitudinally of said member, portions on respectively opposite sides of said seat being bent to form anchors adapted to be embedded 45 in a support, said seat and anchors being located in a single plane, said seat having an integral portion bent to form an arm for attachment to the bar.

2. A device of the class described comprising a supporting member having a seat portion adapted to support a bar extending longitudinally of said member, portions on respectively opposite sides of said seat being bent to form substantially V-shaped anchors 55 adapted to be embedded in a support, said seat having an integral portion folded upon itself to form an arm for attachment to the bar.

3. A device of the class described comprising a supporting member having a seat portion adapted to support a bar extending longitudinally of said member, portions on respectively opposite sides of said seat being

crimped to form substantially V-shaped anchors disposed in the plane of said seat 65 adapted to be embedded in a support, said seat having an integral portion bent to form an arm for attachment to the bar.

4. A device of the class described comprising a wire member having a portion thereof folded upon itself to form an arm adapted to provide a seat for a bar extending longitudinally of said wire, a portion of said arm being adapted to be bent transversely to said seat for attachment to the bar, said member 70 being crimped on respectively opposite sides of said arm to form a pair of substantially V-shaped spaced supports, said seat and supports being located in a single plane.

5. A device of the class described comprising a pair of supporting members arranged in substantially parallel spaced relation, and a spacing element connected to said supporting members, said members having seat portions for supporting a bar, said seat portions 85 having arms for attachment to the bar, portions on respectively opposite sides of each of said seats being bent to form anchors adapted to be embedded in a support.

6. A device of the class described comprising a pair of supporting members arranged in substantially parallel spaced relation, said members having seat portions for supporting a bar, said seat portions having arms adapted 90 to be bent transversely to said seat portions 95 for attachment to the bar, portions on respectively opposite sides of each of said seats being bent to form anchors adapted to be embedded in a support, and a plurality of spacing elements connected to said supporting members and arranged at substantially right angles thereto.

7. A sleeper anchor comprising a wire rod crimped at intervals to provide a plurality of spaced supports, a portion of said rod between adjacent supports forming a seat for supporting a bar extending longitudinally of said rod, said seat being folded upon itself to provide an arm having an eyelet therein, and means adapted to project 100 through said eyelet for securing said arm to the bar.

8. A floor sleeper anchor comprising a wire rod crimped at intervals to provide a plurality of anchors arranged in pairs and 115 adapted to be embedded in a support, the portion of said rod between the anchors of each pair forming a seat for supporting a bar, each of said seats being folded upon itself to provide an arm for attachment to the 120 bar, the portions of said rod between said pairs of anchors being arranged to space said anchors apart longitudinally of the bar.

Signed at Chicago this 16th day of September, 1927.

TELESPHORE JOSEPH SENESAC.
